BRADFORD B. HOLMES, OF NEW YORK, N. Y.

SNUBBER

Application filed April 3, 1924. Serial No. 705,255.

This invention relates to devices for attachment to vehicles for the purpose of modifying undesirable vertical oscillations of the vehicle bodies as the vehicles travel over the road surface.

5 In the particular embodiment of the invention herein described and illustrated, this purpose is accomplished by opposing a resistance to the normal recoil of the vehicle body supporting springs while, at the same time, permitting free compression of these springs. Furthermore, consideration is given to the fact that it is often desired that the normal action of the conventional supporting springs 10 be not affected unless the compression and consequent recoil exceed a predetermined speed, the device being capable of being modified in such manner as to avoid the objectionable stiffening effect on the springs which frequently characterizes the action of devices of 15 this character.

One of the objects of the invention is to provide a device for accomplishing the general purposes above referred to, in which the resistance opposing recoil may be varied from point to point in the recoil movement; that is to say, the instantaneous values of the resistance to recoil may, within limits, be fixed and maintained at any desired predetermined 20 amount.

Another object is to provide a device for the general purposes above described which will be cheap and simple to manufacture and in which the necessity for machining and other relatively expensive processes is avoided.

Another object is to provide a device for the general purposes hereinbefore referred to which will not oppose substantial resistance to recoil unless the normal speed of the recoil 25 movement to be resisted exceeds a predetermined amount.

Another object is the construction of a device for the general purposes above described characterized by the fact that comparatively little stress, is exerted to oppose the supporting springs unless oscillation of the vehicle body takes place; that is to say, the device so functions that when the body and axle are relatively at rest, or substantially at rest, very little pull is exerted tending to draw them to-

gether whether the vehicle as a whole be at rest or in motion.

Another object is to provide a device for the general purposes above mentioned of such construction that the degree of resistance to recoil varies according to the extent of deflection of the supporting springs.

Additional advantages are that a single device is susceptible of being adjusted to vary its resistance within reasonable limits so as to adapt it for use with vehicles of different weights, and that practically all the corresponding parts of the device are interchangeable as to right and left.

Other advantages and objects will be made to appear in the course of this description.

I have shown my invention embodied in a snubber of the type in which the resistance to recoil is largely created by friction. This is for the reason that I have found that snubbers functioning on this principle are in general more satisfactory than any others known to me. It is to be understood, however, that, so far as the inventive feature is concerned, any form of resistance may be used; that is to say, either friction, spring tension, or a combination of both.

Referring to the drawings:

Fig. 1 is a view on the line 1—1 of Fig. 2 showing the preferred embodiment of the invention.

Fig. 2 is a view on the line 2—2 of Fig. 1.

Fig. 3 is a view of the modified form on the lines 4—4 of Fig. 4.

Fig. 4 is a view on the line 3—3 of Fig. 3.

Fig. 5 is a view of a portion of an automobile frame, axle and spring showing my invention in association therewith.

Fig. 6 is a view of a drum similar to that shown in Figs. 1 and 2, but with a modified form of winding seat or reel.

The operative parts are mounted in a cylindrical housing 4 closed at one end for convenience of assembly and access to the interior by the cover plate 5 and provided with a hollow boss 6. The central portion of the cover plate 5 is provided with an aperture 7 to accommodate the washer 8, which is made use of merely because it is better able to stand the strain of the connecting bolt 14 than 100

would be the thin material ordinarily used as a cover plate. Between the washer 8 and the end of the boss 6, is interposed the plate 9, to which is secured the collar 10 which, with the circular projection 11 on the boss serves to center and keep in place the helical springs 12 and 13, the construction and functions of which are hereinafter more fully described. For securing the assembly to the frame of the car the bolt 14 may be employed, this bolt being passed through the washer 8, the plate 9, the bore 15 of the boss 6, and thence through a hole in the frame of the car and secured by a nut 16. If desired, spacing plates 17, 17 may be interposed between the housing and the frame. Whether or not these plates are desirable would depend upon the particular conditions under which the device is to be used. Usually, however, the sides of the front springs are not precisely flush with the side of the frame and in order to attain perfect adjustment the spacing plates are ordinarily desirable. For more rigidly securing the housing to the frame it may further be provided with a lug 18 which lies close to the bottom flange of the frame. By inserting the bolt and assembling the parts as above described and drawing up the nut 16, the housing with its contained parts may be firmly and rigidly secured to the frame of the car.

The interior periphery of the housing serves as a supporting surface for a band of suitable friction material, for instance, ordinary woven brake lining 19, which is secured by any convenient means such as the rivets 20, ordinarily employed for this purpose. While it is not essential to the principle of the invention, I prefer to make use of a lining especially adapted for the purpose, as a metal to metal friction contact besides being noisy and having well-known disadvantages, does not have the desirable high coefficient of friction of the brake lining. While the friction surface of the brake band covers in actual service a relatively small arc, perhaps 90 degrees, the brake band may, if desirable, be carried entirely, or substantially entirely around the periphery of the housing whereby it will fit the floating drum, hereinafter mentioned, closely enough to prevent substantial movement of displacement of the latter. Under any circumstances, however, it is advisable to leave a small gap 21, in the brake lining to allow for any stretching and wrapping effect that might take place in the lining.

The periphery of the housing is provided with a slotted aperture 22 as is likewise the brake lining, the aperture of the latter being indicated by the numeral 23. The slots in the housing and lining register with each other and are of sufficient dimensions to permit the cable 24, hereinafter mentioned, to pass through and to have sufficient freedom of motion in all directions.

The necessary friction for creating resist-

ance to recoil is brought about by the rotation of a floating drum 25 of the brake band. The brake band, in fact, constitutes a bearing which is preferably of a slightly greater radius than the radius of the drum. The slight difference, which is indicated by the numeral 26, is made for the purpose of permitting the drum to rotate freely in the housing when the cable is not put under stress. The cable is not put under substantial stress, as is the case during compression of the supporting springs.

The drum is provided with a channel 27, the bottom 28 of which constitutes a reel or winding seat on which the cable 24 may be coiled through a sufficient arc to take care of oscillations of maximum amplitude in the particular case. In the drawing I have shown the cable coiled on the reel through an arc defined by an angle of approximately 90 degrees the device being assumed to be in place on a car, the relatively moving parts of which are at rest and the cable being assumed to be under the proper tension.

It is also to be noted that the drum is supported only by the inner periphery of the brake lining, the bolt 14 and the boss 6 being free from it and not in any way serving as a journal on which the drum may rotate. The reel or channel may, as a refinement of construction, be provided with a lining 30 of leather fabric, or other suitable material to prevent cutting and excessive wear of the cable. The cable in turn may be fixedly attached to the drum in any convenient way, such as by means of the stop 31, swaged to it and positioned in the aperture 32 which constitutes a broken away portion of the groove in the drum.

It is to be noted that the reel or winding seat 28 is of varying radius with respect to the axis of rotation of the drum. In point of fact it is shown in the drawings as circular and eccentric with respect to it. It is clear, therefore, that as the drum rotates within the housing under any pull exerted on the cable 24 the moment of rotation varies being a minimum when the radius of revolution is shortest and a maximum when the radius of revolution is the longest. On the other hand, the total area of contact, i. e., the friction area between the drum and the brake band remains substantially the same throughout, although, of course, it is slightly varied as the bearing pressure is varied by distortion of the fabric of the lining.

The nature of the variation of the radius of the reel is, it is to be understood, a matter of selection, to be determined in view of the ends to be accomplished. When the body and axle are at relative rest it is, under most conditions, as I have found, preferable that the moment of rotation be relatively great, which means that the radius of revolution is likewise to be relatively great. (By the term "radius

of revolution" I refer to the instantaneous radius indicated by O—A. That is, the radius extending from the axis of rotation of the drum to the point of tangency of the cable 24 with the reel. The length of the radius 5 of revolution accordingly varies with the angular position of the drum.)

When, on the other hand, the supporting springs of the vehicle are compressed, it is 10 usually desirable that the moment of rotation be relatively small. That is to say, that the radius of revolution be relatively short. A reel having these characteristics offers comparatively little resistance to the small vibrations which are sufficiently taken care of by 15 the ordinary springs, while, on the other hand, it exerts a great resistance at the commencement of recoil. If the radius of revolution increases, this resistance accordingly decreases as the body and axle approach their 20 normal relative positions during recoil. From the latter point on during recoil the amount of resistance may be graduated as desired. In the particular case shown in the 25 drawings, the maximum radius of the reel is approximately indicated by the line O—B, and the radius of revolution at normal relative positions of body and axle, by the line O—A. Assuming that the radius O—C becomes the 30 radius of revolution at the commencement of the recoil, it is apparent that the resistance to recoil resulting from friction alone gradually decreases as the recoil approaches its end until the radius O—B becomes the radius 35 of revolution when the resistance to recoil begins to increase. It is, of course, apparent that the character of resistance offered to recoil may be varied, not only by varying the form of the reel, but also by varying the angular position of a given reel at normal 40 position of body and axle. For bringing about variation of the last mentioned method it would simply be necessary (assuming that it was not desired to vary the tension of the 45 springs 12 and 13) to disconnect the free ends of the springs from the studs 34 and rotate the drum to the desired angle and again engage the free ends of the springs with the studs. The best method, however, of adjusting 50 a given device for a definite set of conditions would consist in rotating the drum to the desired angular position for normal position of body and axle, securing the drum in that position, then winding the spring to the 55 desired tension and fastening the end of the cable to the axle, taking up all slack in so doing. A convenient way in which the drum could be held in position during the winding of the spring would consist in inserting a pin 60 29 through a hole 29^a in the housing and brake lining, and thence through a hole 29^b in the drum when the cable has been fastened to the axle the pin is withdrawn. A number of holes similar to that indicated by 29^b may be 65 provided for adjustment of the drum to va-

rious angular positions. A variation of the last described method would consist in winding up the spring by turning the drum, allowance being made in the angular position of the drum at the beginning for producing the 70 desired tension of the springs when the drum had reached the desired angular position for a normal setting.

The means which I have devised for normally maintaining the tension on the cable and for rotating the drum to its normal angular position following its rotation under recoil comprise, in my preferred form shown in Figures 1 and 2, two helical springs 12 and 13 before mentioned, which for convenience are 75 made concentric with each other, one of these springs, for instance, that indicated by numeral 12, being of a greater diameter than the other.

The springs are anchored at diametrically opposite points in the housing, being hooked through the apertures 33. The free ends of the springs are caused to engage the drum by hooking them over studs 34, 34, projecting from the face of the drum. It is apparent 80 that within the limits imposed by the capacity of the springs any desired normal tension in the cable may be created by merely coiling them to the desired degree of tension. As shown in the drawing, variation in the spring 85 tension can be made only in half-circle steps since there are only two studs provided over which the free ends may be hooked. As many studs, however, could be provided as might be desired for purposes of finer adjustment.

The cable may be connected with the axle by any convenient means such as a clamp consisting of the jaws 35, 36, which by means of the bolt 36^a are caused to grip the axle 2, as shown in Figure 5. The ends of the 90 cable may be wound about the button 37 on the jaw 35 and secured in any desired manner.

The springs 12 and 13 perform a further function in addition to those that have been already referred to; namely, that of adding to and increasing, according to their tension, the friction that is set up by the free rotation of the drum in the housing. Even without the springs, it is apparent that at 100 least some friction and consequent resistance to rotation is created by mere weight of the drum, and that even this component of the total friction may be made to offer a very high degree of resistance to rotation if the moment of rotation be made small enough, by sufficiently reducing the radius of the reel. However, the friction thus produced could not be readily varied, aside from the fact that the drum would not return to normal position following recoil of the vehicle springs.

Variation in the tension of the springs 12 and 13, however, produces a variation in the total friction created between the drum and the brake lining. The forces of these springs being applied to the drum at diametrically op-

posite points thus constituting a balanced couple, the drum consequently tends to center itself, and when free from tension of the cable rotates quite freely under the turning moment of the springs. When, however, pull is exerted on the cable, the springs oppose the consequent rotation of the drum, and the latter is thereby forced into close contact with the brake lining, the closeness of this contact depending upon the resistance of the springs to rotation.

In the modified form shown in Figures 3 and 4, a cylindrical housing consisting of the parts 38 and 39 which may be assembled in telescopic fashion is provided. Within the housing there is mounted on the axle 40 a drum 41 of wood or other frictional substance about which is coiled a strap 42, the strap passing around the drum preferably one or more turns and being anchored thereto at a convenient point, such as is indicated by the numeral 43. The drum is capable of rotating freely on the axle except as restrained by frictional resistance and spring tension as hereinafter further described. The part 39 of the housing is provided with a circular concentric depressed portion 43^a, the only purpose of which is to accommodate the nut 44 and thus make it possible to bring the housing close to the frame 45. Washers 46 and 47 may be used for stiffening the frame to enable it to resist the stresses which are imposed by the resistance to recoil. Washer 48 may be also employed, if necessary, to strengthen the housing.

The outer portion of the axle 40 is preferably squared as shown in Figure 4 and passes with a sliding fit through a square bore in the bushing 49 which is merely a convenient way of preventing the axle from turning. The threaded bore 50 in the axle is provided for the purpose of accommodating the screw 51. The screw 51 passes through the star spring 52, the purpose being to increase the friction of the drum 41 as hereinafter further described.

One face of the drum bears against a friction plate 53 consisting of a disk of suitable friction material firmly secured to the part 39 of the housing. The opposite face of the drum 41 bears against another friction plate 54 which is welded or otherwise secured to the bushing 49 as shown in Figure 3. The squared portion of the axle 40 is continued for a sufficient distance to allow slight clearance indicated by the numeral 55. It is apparent, therefore, that, as the screw 51 is turned, the friction between the drum 41 and the friction plates 53 and 54 is varied.

In order to keep the strap 55^a taut at all times, the spring 56 is employed, the spring being anchored to the bushing 49 at its inner end, as indicated by the numeral 57, and at its free end to the stud 58 projecting from side

The drum itself, as is shown in Figure 4, is of varying radius the periphery serving as a reel or winding seat. In the particular embodiment of my invention shown in Figures 3 and 4, the drum is eccentric, but this particular shape is not material it being merely employed because under most conditions it will satisfactorily effect the objects of the invention. The purpose of the variation in the radius, however, is as in the case of the forms shown in Figures 1 and 2 to bring about a corresponding variation in the moment of rotation on the drum and a corresponding variation in resistance to recoil. In other words, as the drum rotates during a recoil movement, the instantaneous values of the resistance to recoil are graduated to best suit the particular conditions in hand. I find that, under ordinary conditions, it is preferable that the amount of resistance at the commencement of a recoil movement be comparatively great, diminishing as the recoil movement approaches its limit. It is the theory of many acquainted with the art, however, that the reverse of this action should take place; namely, the resistance to recoil should continually increase as the recoil movement progresses. To satisfy the various possible requirements, it is apparent that it is only necessary to correspondingly vary the radius of the drum. As in the case of the form of Figures 1 and 2, the housing is provided with a slot 59 of proper dimensions to accommodate and permit free movement of the strap 55^a.

By way of further reference to the characteristics of the modified form of the device shown in Figures 3 and 4, it should be explained that the angular position of the drum, as is shown in Figure 4, is assumed to be the normal position; that is to say, the angular position which the drum may take when the vehicle body and axle are relatively at rest. Under these conditions the greatest radius is indicated by the line O—B, and since the drum is eccentric the smallest radius is indicated by the line O—D. The radius of revolution when the parts are in this position is indicated by the line O—A which is slightly less than the maximum radius. As the drum turns, however, the radius of revolution increases until the maximum radius O—B coincides with it, the result being that there is an increase in the radius of revolution through the arc C A B with a consequent increase in the turning moment and a consequent decrease in the resistance to rotation.

In Figure 6 is shown a drum similar to the drum of Figures 1 and 2, but with a modified form of reel or winding seat. The reel or winding seat of this figure is indicated by the numeral 60. The reel is shown as of somewhat elliptical shape. The change in resistance to recoil when such a reel is used is, therefore, much more rapid than in the case of the circular eccentric reel of Figures 1 and

2, and this form is adaptable for use when it is desired that the resistance to slight oscillations be reduced to a minimum, while the resistance to recoil be a maximum at the commencement of recoil movement.

5 While I have shown and described certain practical specific embodiments of my invention it is to be understood that many of the features described may be varied and yet not 10 depart from the scope of my claims which are as follows:

1. In a brake device a rotatably mounted 15 brake member and a stationary brake member, the rotating member being provided with a reel of varying radius, a flexible draft element coiled on said reel and serving as a draft element for causing rotation of said reel to produce a braking effect the intensity of which varies with the angular position of the 20 drum.

2. In a brake device comprising two relatively rotating brake members having frictional contact one with another for producing braking effect, a reel of varying radius 25 connected with one of said members, and a flexible draft element coiled on said reel, the free end of said draft element being adapted for connection with a moving part the motion of which is to be resisted.

30 3. In a brake device a rotatable drum having a peripheral friction braking surface, a support for said drum and a complementary friction braking surface therefor, the drum being provided with a peripheral groove the 35 bottom of which is of varying radius with respect to the axis of the drum and which serves as a reel, and a flexible draft element coiled on said reel and serving when connected to a moving member and put under tension a 40 means of causing rotation of said drum for the purpose of producing frictional braking effect of varying intensity.

4. In a brake device a stationary brake member, a drum rotatably mounted thereon 45 and having a friction surface in frictional contact with a friction surface on the said stationary member, a reel carried by said drum, and a flexible draft element coiled on said reel and serving as a means of rotating 50 the drum for braking effect at varying moments of rotation.

5. In a brake device a stationary brake member having an interior cylindrical braking surface, a drum rotatable in said member, 55 the periphery of said drum serving as a friction surface to produce friction by rotation of the drum in said stationary member and said drum being also provided with a peripheral groove to receive a flexible draft element 60 for producing rotation and consequent braking effect, the bottom of said groove being of varying radius with respect to the axis of rotation of the drum.

6. In a device for the purpose indicated a 65 rotatable member; a fixed journal bearing

member adapted for mounting on one of the two spring-separated members of the vehicle to be served; the rotatable member having a seat upon which a flexible connector may be wound in the rotation of the said rotatable member; a flexible connector attached at one end to the rotatable member and passing over said seat and extending therefrom in direction for attachment to the other of said 70 spring-separated members of the vehicle; a

75 fixedly mounted friction plate and means for stressing said plate and the rotatable member against each other, the parts being formed and dimensioned to render the pressure and area of frictional contact between the rotatable member and the friction plate, substantially constant throughout the range of rotative movement; the seat for the flexible connector being eccentric with respect to the fixed journal bearing member, whereby the radius

80 of leverage for rotation against the frictional resistance increases in one direction of rotation and diminishes in the opposite direction while the friction remains constant.

85 7. In a device for the purpose indicated a rotatable member; a fixed journal bearing member adapted for mounting on one of the two spring-separated members of the vehicle to be served; a spring connected with the journal bearing member and with the rotatable member for being tensioned by rotation of the latter in one direction and rotating said latter in the opposite direction by its reaction, the rotatable member having a seat

90 upon which a flexible connector may be wound in the rotation of said rotatable member; a flexible connector attached at one end to the rotatable member and passing over said seat and extending therefrom in a direction for attachment to the other of said spring-separated members of the vehicle; a fixedly mounted friction plate and means for stressing said 95 plate and the rotatable member against each other, the seat for the flexible connector being eccentric with respect to the fixed journal bearing member, whereby the radius of leverage in favor of the connector for tensioning the spring in unwinding the connector from the seat, diminishes from a certain point in the unwinding which increases the tension of

100 105 the spring.
